CLUTCH TYPE SPEED RESPONSIVE DEVICE
WITH MAGNETIC LINK

George A. Winterburn, Putnam, Clarence B. Walworth, Rocky Hill, and Leroy E. Lawrence, Putnam, Conn.; said Walworth and said Lawrence assignors to said Winterburn

Application March 31, 1951, Serial No. 218,631

22. Claims. (Cl. 264—13)

1

This invention relates to a device for transmitting motion through combined hydraulic and magnetic links, particularly as applied to switches for indicating or making effective the motion or rest condition of a driving mechanism, for the purpose of controlling it or associated devices.

It is frequently desirable to supervise or control the mode of operation of machines having rotary or other motions. Examples of such supervision or control are remote indication of the response of an electric motor to the operator's control, protective supervision of a motor to insure that it has slowed down or stopped before reverse power is applied, control of one machine according to the operation of another machine, introduction of a time delay between the start of one operation and the start of another, and analysis of various machine functions.

Objects of the present invention are to provide an improved actuating device which responds to rotary motion in either direction, which distinguishes between directions of motion and between motion and standstill, which permits counting by providing an impulse per revolution of a shaft, which provides an interlock between various moving parts of an installation, which can be used as a jogging switch and interlock for devices such as conveyors, and which selectively operates a plurality of independent switches according to the motion or rest condition of the mechanism under study or control. Other objects are to introduce an adjustable or fixed time delay between the application of driving motion to a device and actuation of dependent devices such as switches accordingly, to provide a zero motion indicator, and to provide a device of the general type indicated above which is simple and inexpensive and yet rugged, reliable, accurate and particularly also very versatile for application to a large variety of functions.

Devices according to the invention comprise a housing containing viscous liquid, a driving element such as a disk and a driven member such as another disk, mounted in the housing with driving and driven portions adjacent to each other and with the liquid providing hydraulic coupling between the two portions, means for transmitting movement to the driving element, an actuated member, a magnet or iron element carried by one of the two members, and a magnet or iron element carried by the other member, magnet and iron elements being placed magnetically to respond to a change of position therebetween, whereby movement of the driving element causes change of position of

2

the driven member affecting the actuated member. Preferably the actuated member is a switch, but any mechanical operator can be used instead, such as a lever for moving a signaling element or opening or closing a latch or lock mechanism. Biasing means such as a weight eccentrically mounted on the driven member, or spring means are used for yieldingly urging the driven member to hold its magnetic element in a normal position, so that rotation of the driving element causes the driven member to move the magnet to a position displaced clockwise or counterclockwise from the normal position to affect the other magnetic element and to actuate the device. If one or a plurality of actuated members are disposed with their magnetic elements such as iron armatures adjacent the path of the driven magnetic element, at normal position or at one or more displaced positions on each or either side of a normal position or at both normal and displaced positions, these members can be actuated in a variety of ways, independently or discriminatory of the direction of rotation.

25 To provide for a minimum starting speed and to introduce a time delay between the beginning of rotation of the driving element such as a disk and the actuation of one of the devices through the driven member such as another disk, the liquid coupling between the disks can be varied so that rotation of the driving disk does not move the driven disk sufficiently to affect the magnetic element of the actuated device, or to introduce a predetermined slip between driving element and driven member. The magnitude of liquid coupling can be varied by changing the bias such as weight of the magnet or other part mounted on the driven member, by changing the viscosity of the liquid in the housing or, with particular convenience, by adjusting the spacing between the disks.

30 In a further aspect the driven member carries one or more abutments, and the housing or a structural component referred thereto carries a stop disposed in the path of an abutment so that when the driving element moves the driven member the abutment engages the stop to hold the driven member in a predetermined position, the magnetic element of one or more of the actuated devices being located in corresponding position. A plurality of abutments can be disposed in spaced positions on the driven element to move along spaced paths, the stop being adjustable into a selected path thereby preselecting

35

40

45

50

55

the position of magnetic elements of the driven member and the actuated device.

In a more specific aspect the disks constituting driving element and driven member are only partially immersed in the viscous liquid, and are disposed with opposed faces parallel and closely adjacent to provide a capillary space for the viscous liquid therebetween, the disks being effectively coupled by a controllable capillary force acting in the space, so that when the driving disk is rotated liquid will be distributed over said faces and the driven disk will be coupled to the driving disk with the above mentioned speed discrimination and time delay.

These and other objects and aspects of the invention will be apparent from the following description of several embodiments which refer to a drawing wherein

Fig. 1 is a side elevation of an actuator according to the invention;

Fig. 2 is an end elevation corresponding to Fig. 1;

Fig. 3 is a section on line 3—3 of Fig. 2, with parts in elevation;

Fig. 4 is a section on line 4—4 of Fig. 3;

Fig. 5 is an enlarged section similar to Fig. 3, through switch and housing, with the magnet in elevation and the other parts omitted;

Fig. 6 is a section corresponding to Fig. 4 of a second embodiment; and

Fig. 7 is a section similar to Fig. 5 of a third embodiment of the invention, certain parts being omitted in Figs. 6 and 7.

The embodiment of the invention which is illustrated in Figs. 1 to 5 has a housing 1 enclosing a chamber partially or wholly filled with a viscous liquid 2 such as hydraulic fluid of selected viscosity and mounting a shaft 3 which carries a driving disk 4 fixed to the shaft and a driven disk 6 freely rotating on the shaft. The driven disk 6 carries a small permanent magnet 7 at its periphery. Mounted outside the housing is a mercury switch 8 or mechanical device 8a (Fig. 7) having a movable iron element 9 or 9a respectively. It will be noted that the magnetic elements 7 and 9 define a comparatively concentrated region of optimum response therebetween.

The housing 1 has a journal box 11 in which are mounted two roller bearings 12 and a conventional sealing ring 13 respectively for supporting the shaft 3 and preventing loss of the hydraulic fluid 2. The driving disk 4 is spaced from the inner bearing 12 by washers 14 and fixed to the shaft 3 with a screw 16. The inner end of the shaft 17 is of reduced diameter to form a shoulder 18, the reduced portion being threaded to receive a nut 19 for clamping the inner race of a roller bearing 21 against the shoulder 18. The driven disk 6 is secured to the outer race of bearing 21 by a set screw 22, the driven disk 6 being free to rotate independently of the shaft 3, except as will be described hereinafter.

The driven disk 6 carries near its periphery a magnet 7 for example secured by a machine screw 24 to a rearwardly extending boss 23. The magnet 7 is held close to the rear wall 26 of the housing, which rear wall is formed of non-magnetic material such as molded plastic.

Attached at the rear of the housing 1 is a bracket 27 to which one or more spring detents 28 for firmly holding a mercury switch 8 are attached by screws 29 passing through holes 31. Other mounting holes 31a and 31b are provided to attach additional detents (not shown) for

holding additional switches serving purposes to be set forth below.

As shown in Fig. 5 the mercury switch 8 can be of conventional design with a glass envelope 30 and two leads 32 one of which extends into a pool of mercury Hg while the other is electrically connected through a spiral spring 33 to the armature 9 with wire finger 34 which dips into the pool of mercury thus completing an electrical circuit when the magnet 7 attracts the armature 9. Instead of the mercury switch 8, a pivoted lever 8a of a mechanical actuator may be mounted adjacent the rear wall 26 of the housing 1 as shown in Fig. 7. The lever 8a carries an armature 9a, and it will be understood that in this and analogous embodiments with little limitation on size or weight of the armature, components 7 and 9a, constituting magnetic elements, can be interchanged. It will be further apparent that the separating wall 26 can be part of a larger compartment, the magnetic link 7, 9 providing for mechanical separation of driven member 6 and actuator 8 or 8a. Instead of a magnet and an iron armature, two magnets can be used as magnetic elements.

In the position shown in Fig. 5 with magnet 7 opposite armature 9, the latter is attracted, making contact at Hg and 34 as indicated in dot and dash outlines.

As shown in Figs. 3 and 4 the driven disk 6 carries a pair of vanes or abutments 37 near its periphery. A screw 38 fastened in the top of the housing 1 extends with its end into the path of the vanes 37 for the purpose of stopping rotary motion of the driven disk in either direction when the magnet 7 and the vanes 37 are in one of the positions 7a shown in Fig. 4 in dot and dash lines. In either of these positions the magnet 7 will operate a mercury switch held in one of the clips or detents mounted by means of holes 31a (Fig. 2) as described above. The armatures of these switches can be disposed in appropriate positions to either side of the central position shown in Figs. 2 and 3. It will be further understood that the lateral distances of these armatures can be rendered adjustable by appropriate conventional means.

As shown in Fig. 6 two or more vanes or abutments 37a or 37b may be provided at either side of a line passing through the shaft axis and the magnet 7 in neutral position. The abutments 37a nearest that line are located nearer to the axis of the disk than vanes 37b. In this embodiment a modified stop screw 38a is adjustable radially of the driven disk so that it can be moved into the paths of the outer vanes 37b as shown by its position in solid lines in Fig. 6 or into the path of the inner vanes 37a as shown by its position shown in broken lines 38b so that it can be selectively stopped by either a vane 37a or 37b respectively.

When the stop screw 38a is in the position shown in broken lines the driven disk will be stopped in one of the broken line positions 7a of the magnet. When the stop screw 38a is in the position shown in solid lines the driven disk will be stopped with its magnet in one of the broken line positions 7b. As already indicated, switch means 8 or mechanical actuator devices 8a may be mounted at positions corresponding to detent mounting holes 31a or 31b which again correspond respectively to vanes 37a or 37b. The switch 8 can also be moved from a detent secured to the holes 31a to a detent secured in the

holes 31b as the stop screw 38a is adjusted to the path of vanes 37b.

As shown in Figs. 2 and 3 the housing 1 is provided with an opening 41 providing access to the set screw 22 which fastens the disk 6 to the bearing 21. A screw 42 provides a closure for the opening 41.

The operation of the actuator is as follows.

Assuming that the actuator is mounted in the position shown, the weight of the magnet 7 normally holds the driven disk 6 in the rest position shown in the drawing in solid lines. In this position the magnet 7 is in operative relation to armature 9 (Fig. 5) or 9a (Fig. 7) such that the armature causes the switch 8 to close or the actuating lever 8a to move to a desired position. When the driving shaft 3, which is connected to a rotating mechanism, for example the shaft of a motor begins to rotate, the hydraulic liquid effectively couples the driving disk to the driven disk causing the driven disk to rotate in the same direction. The disk and magnet return to normal position, reactivating switch 8, only upon stoppage, or if desired minimum speed, of the driving member.

If the housing 1 is full, or nearly full, of hydraulic liquid 2 the driven disk will respond relatively quickly. If the housing is only partially full as shown in Figs. 2 and 4, the hydraulic liquid will be drawn between the disks at a certain rate until sufficient interfacial friction or capillary attraction is provided to overcome the tendency of the magnet or other weight to hold the driven disk in normal or rest position. In addition to amount of liquid and speed rotation, the response time also depends on the viscosity of the liquid and the spacing between driving and driven disks. The disk will then move the magnet to the position defined by stop 38 or to one of the positions 7a or 7b. More time is needed to lift the magnet to a more remotely displaced position such as 7b than to a less remotely displaced position such as 7a.

As the magnet moves from its normal position it will move out of operative relation with the switch 8 allowing the armature located adjacent the normal position 7 of the magnet to move its contact finger 34 from the mercury pool, with a certain time delay between beginning of motion and actuation of the switch. When the magnet 7 moves into one of the displaced positions 7a or 7b it will remain there operating the armature of a switch if such is located in that position. Whether the driven disk moves in either clockwise or counterclockwise direction the switch at neutral position will be allowed to open. If switches are mounted at the displaced positions one of them will be actuated. Thus the switch at normal position may be employed to discriminate between rotation and non-rotation of the mechanism attached to the driving shaft 3, while switches located adjacent displaced positions 7a or 7b can be used to indicate the direction of rotation of the shaft.

Displaced switches alone, without normally affected switch 8 will perform the function of switch 8, as well as the directional function, with an additional time delay, if desired adjustable by means of a stop similar or analogous to screw 38a.

The return time upon stoppage of shaft 3 or rotation falling below a given rate can be adjusted to determine time intervals between respective conditioning of two switches in posi-

tions such as 31 and 31a, or between actuation and reactivation of a single switch at 31.

If the stop 38 is entirely withdrawn, the actuator can be used as a counter effecting one or 5 more impulses per shaft rotation, the phase relation of movement and impulse and the number of impulses depending upon the arrangement of switches and selection of coupling characteristics.

In addition, switches located at displaced positions will give a qualitative indication of the speed of the shaft, since a switch located adjacent a less remotely displaced position such as 7a will respond at a given speed prior to the response of a switch located at a more remotely 15 displaced position such as 7b; analogously, two switches at different positions will respond to different speeds with the same time delay. Generally speaking, the three variables, switch position, speed of driving member and response delay, can be definitely interrelated.

The time delay between the beginning of rotation of the driven disk 4 and the operation of a switch may be controlled or adjusted by varying either the hydraulic coupling between the disks 25 or the adjustment of the stop screw 38a or the vane positions, or by changing the bias of the driven disk 6. This can be done by changing the weighting means of driven disk 6, or by adjusting biasing means which are independent of 30 gravity. Fig. 6 shows as such means springs 51, 52 interposed between housing 1 and disk 6. Such springs can be rendered adjustable by conventional means and set to bias the driven member in the desired normal position. The hydraulic coupling between the disks may be increased by replacing the fluid with one of higher viscosity, by increasing the amount of fluid in the housing, or as previously mentioned, by decreasing the space between the two disks. For the 35 latter purpose the housing has been provided with the opening 41 which affords access to the set screw 22. By inserting a screw driver through this opening the set screw 22 may be loosened and the driven disk shifted axially on the bearing 21 to adjust the spacing between the disks. The weighting of the driven disk may be increased by replacing the magnet 7 with one of greater weight, or by adding a non-magnetic weight. As previously described the stop 38a may be adjusted in or out of the paths of one of the stop vanes 37a or 37b thereby determining the angle through which the driven disk may rotate and also selecting a switch at one of the 40 displaced positions 7a or 7b for continuous operation by the magnet 7.

By proper choice of the various effective characteristics such as fluid viscosity, degree of filling, disk distance and biasing force, a minimum effective speed as well as predetermined time delay of actuation upon reaching such speed can be selected to effect response of a switch or switches or other actuators at either normal or displaced position. Thus a switch 8 in the position of Fig. 2 can be made to respond only if the shaft 3 rotates at a given speed, with predetermined time delay after that speed is reached.

By differently distancing the corresponding driven stops (such as 37) on either side of a fixed stop (such as 38), different response speeds and time delays can be provided for respective senses of movement. Adjustability of these distances and of the corresponding response characteristics can be provided by conventional means applied to movable or fixed stops or both. 70 It will now be evident that devices built in

accordance with the invention are adaptable to various purposes involving functions such as time delay, juggling, directional discrimination, distinction between operation and non-operation, speed detection, interlocking of several components, speed limiting, supervision of reversing, overrunning control, protection against back spin, counting, and combinations of such functions.

It should be understood that the present disclosure is for the purpose of illustration only and that this invention includes all modifications and equivalents which fall within the scope of the appended claims.

We claim:

1. An actuator comprising a housing containing viscous liquid, a driving element and a driven member mounted in said housing with driving and driven respectively adjacent to each other with said liquid providing hydraulic coupling therebetween, means for transmitting movement to the driving element, an actuated member mounted outside said housing, a concentrated magnetic element carried by one of said members, a second concentrated magnetic element carried by the other member, and stop means for limiting conjoint movement of said driving element and said driven member, said magnetic elements being placed relatively to said stop means to move said actuated member upon change of position therebetween, whereby movement of the driving element causes delayed response of said actuated member.

2. Actuator according to claim 1 further comprising biasing means yieldingly urging the driven member to hold its magnetic element in normal position, whereby rotation of the driving element causes the driven member to change said position, affecting said actuated member.

3. Actuator according to claim 1 wherein said stop means includes corresponding stop members mounted on said driven member and said housing respectively, to stop movement of the driven member after initial movement, while said driving element continues to move.

4. An actuator comprising a housing containing viscous liquid, a driving rotatable disk and a driven rotatable disk both mounted in said housing with said liquid providing hydraulic coupling between the disks, means for transmitting rotary movement to the driving disk, a concentrated magnetic element carried by the driven disk, stop means for limiting conjoint movement of said disks, and an actuated device having a concentrated magnetic element fixed relatively to said housing to respond to a change of position between the magnetic elements.

5. Actuator according to claim 4 further comprising means for biasing said driven disk to urge its magnetic element to a normal position, whereby rotation of the driving disk causes the driven disk to move its magnetic element from said normal position to affect said actuated device.

6. Actuator according to claim 5 wherein said biasing means normally urges the magnetic element of said driven disk to a normal position and wherein said second magnetic element is located adjacent said normal position, whereby rotary movement in either of two directions actuates said device.

7. Actuator according to claim 5 wherein said biasing means normally urges the magnetic element of said driven disk to a normal position and wherein said second magnetic element is disposed at a location adjacent the path of the

first magnetic element but spaced from said normal position, whereby said device is actuated by rotary movement in one direction.

5 8. Actuator according to claim 5 comprising an additional actuated device said driven disk being normally biased to urge its magnetic element to a normal position and said two actuated devices being located with their magnetic elements adjacent the path of the magnetic element of the driven disk at each side of said normal position respectively, whereby one of said devices is operated according to the direction of said rotary movement.

15 9. Actuator according to claim 5 having two additional actuated devices and being characterized in that said driven disk is normally biased to urge its magnetic element to a normal position and in that said three actuated devices are located with their magnetic elements adjacent 20 the path of the magnetic element of the driven disk, one element adjacent said normal position, and one of the remaining elements at each side of said normal position respectively, whereby one of said devices is selectively actuated in the absence of said rotary movement or by rotary movement in either direction respectively.

25 10. Actuator according to claim 5 wherein said biasing means comprises spring means interposed between said driven disk and said housing to urge its magnetic element to a normal position, whereby rotation of the driving disk causes the driven disk to move its magnetic element from said normal position and to affect said device.

30 11. Actuator according to claim 4 wherein said driven disk carries a magnet and said actuated device carries an iron armature element.

35 12. An actuator comprising a housing containing viscous liquid, a driving rotatable disk and a driven rotatable disk both mounted in said housing with a space therebetween and with said liquid providing hydraulic coupling through said space, means for transmitting rotary movement to the driving disk, a magnetic element carried by the driven disk, an actuated device having a magnetic element fixed relatively to said housing to respond to a change of position between the magnetic elements, and means for adjusting said coupling thereby to vary a predetermined period between initiation of driving and effective change of position between the magnetic elements.

40 13. Actuator according to claim 12 characterized in that said adjusting means comprises means for varying the space between said disks.

45 14. Actuator according to claim 13 further characterized by shaft means adjustably carrying said driving disk, bearing means for rotatively supporting said driven disk on said shaft means and means for adjusting the distance between said disks.

50 15. Actuator according to claim 14 wherein said driving disk is fastened to said shaft and said driven disk is axially adjustable on said bearing.

55 16. The actuator according to claim 14 wherein said driven disk is fastened to said bearing with a set screw and said housing has an opening affording access to said screw.

60 17. An actuator comprising a housing containing viscous liquid, a driving rotatable disk and a driven rotatable disk both mounted in said housing with said liquid providing a hydraulic coupling between the disks, means for transmitting rotary movement to the driving disk, a

magnetic element carried by the driven disk, an abutment mounted on the driven disk, a stop mounted on the housing and disposed in the path of said abutment to hold the driven disk in a displaced position after a predetermined period of rotation of the driving disk causing the driven disk to move its magnetic element from a normal position to said displaced position, and an actuated device having a magnetic element fixed in predetermined position relatively to said stop, whereby the two magnetic elements can be held in predetermined relative position during rotation of the driving disk.

18. Actuator according to claim 17, wherein said driven disk carries an abutment on either side of said stop.

19. Actuator according to claim 17 characterized in that said driven disk carries a plurality of abutments radially spaced to stop the driven disk in at least two displaced positions at one side of said stop, said stop being adjustable selectively to extend into the path of one of said abutments.

20. An actuator comprising a housing containing viscous liquid, a driving rotatable disk and a driven rotatable disk mounted in said housing, said disks being only partially immersed in said liquid, means for transmitting rotary movement to one of the disks, a concentrated magnetic element carried by the other disk, and an actuated device having a second concentrated magnetic element fixed relatively to a normal position of the first magnetic element to respond to a change of position between the two elements, the opposed faces of said disks being distanced to form a capillary space for liquid therebetween so that said disks are coupled by a predetermined capillary force, whereby the driving disk when started by said transmitting means distributes liquid over said faces and the driven disk is moved to affect said device after a time interval dependent upon the building up of said capillary force.

21. Actuator according to claim 20 characterized by means for adjusting the spacing between said disks to vary said capillary force, whereby said interval may be varied.

22. An actuator comprising a housing containing viscous liquid, a driving rotatable disk and a driven rotatable disk both mounted in said housing with said liquid providing hydraulic coupling between the disks, means for transmitting rotary movement to the driving disk, a concentrated magnetic element carried by the driven disk, stop means for limiting conjoint movement of said disks, an actuated device having a concentrated magnetic element fixed relatively to said housing to respond to a change of position between the magnetic elements, and biasing means including an eccentric weight on said driven disk for biasing the driven disk to urge its magnetic element to a normal position, whereby rotation of the driving disk causes the driven disk to move its magnetic element from said normal position and to affect said device.
